US00D802207S

(12) **United States Design Patent** (10) Patent No.: **US D802,207 S**
(45) Date of Patent: ** Nov. 7, 2017

(54) **MOUTHPIECE OF A SMOKING ARTICLE**(71) Applicant: **Altria Client Services LLC**,
Richmond, VA (US)(72) Inventors: **Alistair Bramley**, Richmond, VA (US);
George Stafford, Richmond, VA (US);
Eric Hawes, Midlothian, VA (US);
Traci Martin, Richmond, VA (US);
Berina Yerkic-Husejnovic, Richmond,
VA (US)(73) Assignee: **Altria Client Services LLC**,
Richmond, VA (US)(***) Term: **15 Years**(21) Appl. No.: **29/591,099**(22) Filed: **Jan. 17, 2017****Related U.S. Application Data**(60) Division of application No. 29/561,106, filed on Apr.
13, 2016, now Pat. No. Des. 779,725, which is a
continuation of application No. 29/503,697, filed on
Sep. 29, 2014, now abandoned.(51) **LOC (10) Cl.** **27-02**(52) **U.S. Cl.**USPC ..... **D27/170**(58) **Field of Classification Search**USPC D27/101, 105, 108, 123, 129, 163, 164,

CLAIM

The ornamental design for a mouthpiece of a smoking article, as shown and described.

DESCRIPTION

FIG. 1 is a perspective view of a mouthpiece of a smoking article showing our new design.

FIG. 2 is a side elevational view thereof; and,
FIG. 3 is a right end elevational view thereof.
The broken lines depict portions of the mouthpiece of a
smoking article and form no part of the claimed design.
